UNITED STATES PATENT OFFICE.

PATRICK McDONALD, OF ROCHESTER, NEW YORK, ASSIGNOR OF ONE-HALF TO GEORGE HERBERT SMITH, OF ROCHESTER, NEW YORK.

FUSE-HOLDER FOR ELECTRIC-CIRCUIT CONDUCTORS.

No. 884,519.

Specification of Letters Patent.

Patented April 14, 1908.

Application filed October 2, 1905. Serial No. 280,977.

To all whom it may concern:

Be it known that I, PATRICK McDONALD of Rochester, in the county of Monroe and State of New York, have invented certain new and useful Improvements in Fuse-Holders for Electric-Circuit Conductors; and I do hereby declare the following to be a full, clear, and exact description of the same, reference being had to the accompanying drawings, forming a part of the specification, and to the reference-numerals marked thereon.

My present invention has for its object to provide a fuse holder or terminal head for conductor or line wires, such as are used particularly for telephones and telegraph lines, which are frequently bound into a cable the several wires thereof terminating at a common station from which lead the extension wires connected to the separate instruments.

My invention has for its further object to provide a holder in which the fuse may be protected so that if it is burned out by an excessive voltage on the line, from any cause, no damage can result to the fixtures or other adjacent parts and a new fuse may be quickly inserted without requiring the use of special tools.

To these and other ends the invention consists in certain improvements and combinations of parts all as will be hereinafter more fully described, the novel features being pointed out in the claims at the end of the specification.

In the drawings: Figure 1 is a side elevation of the device constructed in accordance with my invention. Fig. 2 is a longitudinal sectional view thereof. Fig. 3 is a detail cross sectional view taken on the line 3^x-3^x of Fig. 2. Fig. 4 is a detail perspective view of one of the closure pieces.

Similar reference numerals in the several figures indicate similar parts.

A fuse holder or terminal head embodying my invention is designed particularly to provide means for supporting or holding the fuse wire, which is usually interposed in the line wires of an instrument circuit to prevent the latter from injury from excessive voltage of current accidentally received on the wire from any source, so that the fuse may be protected from atmospheric conditions as well as from accidental injury and when destroyed by being burned out it may be readily replaced.

In illustrating the present embodiment of my invention I have shown the device as comprising a seat piece 1 having a threaded stem 2 provided with a nut 2^a forming means for securing the holder to a support, such as a frame piece 3, and in order to perfectly insulate the seat from the support the stem is surrounded with a bushing 4 of insulating material at the ends of which are washers 5 of similar material and larger in diameter than the bushing to overlap opposite sides of the support, as shown. The seat 1 is recessed or cup-shaped and adapted to receive one end of a shell or fuse holder 6 which in the present instance is shown as a tube and containing the fuse wire 7 but the shell may be otherwise constructed to receive said wire without being a closed tube although I deem that to be the preferable form. The outer end of the holder is closed by a recessed cap 8 and this in turn is provided with a screw 9 forming means for binding the one terminal *a* of the line the other terminal *b* being conveniently attached to the seat 1 by passing it beneath the nut 2^a.

To facilitate the application of the fuse wire the holder is provided at each end with shallow depressions or grooves 10, of a depth less than the diameter of the fuse wire, into which the ends of the wire are placed after being bent over the ends of the holder. This enables one end of the latter to be inserted into the seat piece 1 and the cap piece 8 to be applied to the other end thereof with the ends of the fuse wire in frictional engagement with the inner surfaces of said pieces. Near each of the ends of the holder a notch or annular groove 11 is provided which is adapted to receive an inwardly extending projection or point 12 on a spring finger 13 located on the sides of the seat and cap pieces.

From the foregoing it will be seen that the seat and cap pieces 1 and 8 are separated from each other by the holder 6 and when the fuse wire is intact it places them in electrical connection, but if a current of sufficiently high voltage passes over the line the fuse may be destroyed without the liability of damaging adjacent parts and as the fuse is entirely inclosed within the holder there is no liability of igniting or otherwise injuring other apparatus arranged in proximity thereto. When it becomes necessary to replace the

fuse an operator may withdraw the cap 8 by exerting sufficient force thereon to disengage the projection 12 thereon from the recess 11 and by a similar operation he may remove 5 the holder 6 from the seat piece 1. A new fuse of the required length may then be inserted, its ends bent over the ends of the holder and secured in the grooves or recesses 10, as before described, when the parts may 10 be re-united and the line circuit restored.

A device such as I have described is simple in construction as the seat and cap pieces 15 may be made of metal and the insulating portions such as the bushing 4, the washers 5 and the holder 6 may be made of porcelain, gutta percha, or indurated fiber and their lengths, or diameters, increased or diminished as the requirement of special or pecul-

iar conditions under which the device may be used may necessitate.

I claim as my invention:

In a device of the character described, the combination with a seat piece provided with a recess, a cap piece having a similar recess and an insulating shell having ends adapted to fit said recesses and provided with notches, of spring fingers on the seat and cap pieces coöperating with the notches to detachably secure the parts together, a fuse wire contacting with the seat and cap and binding devices on the latter parts.

PATRICK McDONALD.
